UNITED STATES PATENT OFFICE.

CHARLES W. LYNCH, OF PERRY, OKLAHOMA, ASSIGNOR TO WILLIAMS IRON WORKS COMPANY, INCORPORATED, OF TONKAWA, OKLAHOMA.

WRENCH.

Application filed January 13, 1928. Serial No. 246,611.

This invention relates to wrenches, but more particularly to a wrench for use in connection with the coupling and uncoupling of sucker rod lines used in the pumping of oil wells. As well known, the customary method of coupling sucker rods is by means of engaging a threaded pin and a thread socket, the threads of each being partially imperfect so that when finally screwed home there is great frictional resistance against unscrewing of the joint. Great power is therefore required in finally screwing up a joint, "bucking up" as called, or in the initial "breaking out" of a joint preliminary to unscrewing the members.

One of the objects of this invention, therefore, is to provide a wrench having a loose or oscillating handle which may be swung in an arc to gain momentum and then brought with great force against the wrench head to assist in "bucking up" or "breaking out" a joint, or for that matter any threaded connection. The connection between the wrench head and handle is of such nature with the new and improved construction of this invention, that practically the entire reaction of the blow shall be absorbed by the heavy head and not imposed on pivot pins or like relatively fragile parts.

A further object of the invention is to produce a wrench of the character above-outlined which is provided with means whereby the head and handle may be readily interlocked when desired, so that the parts shall constitute a rigid wrench. This is particularly desirable when a connection is being "spun in" or "spun out", at which time the frictional resistance is not great, and the operator in his manipulation of two wrenches, one above and one below the joint, swings the wrenches in a complete circle, changing hands on each wrench after each half circle, it being evident that if the handles were loose on the heads, this operation would be greatly impeded.

Another object of the invention is to provide a wrench having a sliding extension sleeve or handle whereby the length of the lever arm may be readily varied at will according to the resistance to be overcome.

A still further object of the invention is to produce an improved wrench head or jaw of the type designed for engagement with a particular shape, that will not fall from engagement with the object to be gripped should the handle be released by the operator. This

construction is especially advantageous for sucker rod use as should the operator miss his "grab" or changing of hands in a "spinning" operation, the wrench will not fall from the sucker rod to the floor of the derrick. 60

With the general objects named in view, the invention consists in certain novel and useful features of organization and combinations of parts as hereinafter described and claimed; and in order that it may be fully understood, reference is to be had to the accompanying drawing, in which:—

Figure 1 is an elevation of a wrench embodying all of the features of invention, said wrench being illustrated with the handle and head in interlocking position. 70

Figure 2 is a longitudinal section through the sleeve of the wrench handle, the handle being shown in dotted lines in its extended position with the wrench head and handle 75 loose for imparting blows to the head.

Figure 3 is an elevation of the end of the wrench head.

Figure 4 is a section on the line IV—IV of Figure 1. 80

Figure 5 is a section through the handle to illustrate the rear end of the wedge which interlocks the handle and head.

Figure 6 is a section on the line VI—VI of Figure 2. 85

In the said drawings, where like reference characters indicate corresponding parts in all of the figures, 1 indicates a wrench head formed with an operating jaw 2 to provide a gripping space which will snugly embrace the object to be turned which is indicated at A as a sucker rod "square." In order to provide means which will operate to hold the wrench on the rod A should the handle be released by the operator, a jaw 3 is formed on said wrench head in opposition to the jaw 2, and a space B is provided between said jaws whereby the wrench can be engaged with the rod A as will be readily understood. It will be apparent that when a long sucker rod is engaged by the wrench, if the wrench is released by the operator, the end of the handle will swing in an arc until the auxiliary jaw 3 contacts with the rod A on the side opposite from jaw 2. The wrench will thus maintain 100 its engagement with the rod, but at a downwardly extending angle therefrom. The jaw 3 has a further function in connection with the other features of the invention as will hereinafter appear. 110

Adjacent jaw 2 the wrench head is formed with a semi-circular pocket 4 within which the rounded end or head 5 of a handle 6, comprising an I-shaped member having a web 7 and flanges 8, is adapted to oscillate, it being noted in this connection that the flange 8 adjacent the jaws of the wrench merge into the arc of the circular head 5. In the construction illustrated the handle 6 is held tightly for oscillation with a bearing contact against the socket, by a slip 9 bolted as at 10 or otherwise secured with the socket of the wrench head. The rounded head 5 thus has a tight bearing contact with the pocket 4 against the entry of abrasive matter and the handle can be swung in an arc and its flange 8 forming a hammer can be brought with great force against the straight portion of the wrench head, constituting an anvil, to impart heavy hammer-like blows to unscrew or screw up a rod A.

To provide means for readily interlocking the handle and the head to provide a fixed-handle wrench when desired, the end of the handle 6 is received within a slidable sleeve 10^a, preferably corrugated for convenience of the operator, said sleeve being provided with a controlling rod 11 forwardly projecting from the handle and having adjusting nuts 11^a for taking up wear. The rod 11 is engaged at its opposite end with a sliding wedge 13 provided with side ears 14 encircling the flange 8, it being evident that by moving the sleeve toward the head, the wedge may be slid in between the face of the slip 9 and the back of the handle 6, thus resulting in producing a fixed-handle wrench.

To hold the sleeve 10^a in any desired position of adjustment, a series of lugs 14^a are cast on one side of the web 7 adjacent the flange 8, said lugs being notched as at 15 to provide for unimpeded sliding action of the ears 14 of the wedge 13. Mounted between said web 7 and the sleeve 10^a is a spring-actuated locking bolt 16 working through an opening in the side of the sleeve and having a thumb-operated member 17 working in a slot 18 in the sleeve, whereby the bolt 16 may be engaged or disengaged between any pair of lugs 14^a and the sleeve consequently fixed in any desirable position of extension.

The sleeve is held against accidental dislodgment from the handle 6 by a locking bar 19 secured by a machine screw 20 engaged in the handle 6, said bar contracting with the locking bolt 16 if the sleeve is extended be-

yond a certain point. It will be noted in this connection that the flange 8 is omitted from the handle 6 on one side of the web 7 so that the locking bolt may be free to operate as 60 above-described.

Although the use of the various parts is believed to be clearly apparent from the above description, it is desired to point out that in operation, when the worker desires to shift 65 from a loose-handle wrench to a fixed-handle wrench, he merely retracts the bolt 16 with his thumb and then pushes the sleeve inwardly. In this operation it is apparent that the rod A will be disengaged from jaw 2 but will 70 be immediately engaged with jaw 3, continued pressure by the operator on the sleeve effects entry of the wedge between the back of the handle 6 and the slip 9 as pointed out, and effectually provides a fixed-handle 75 wrench.

It is believed the construction and operation of the wrench has been so set out that further recapitulation is unnecessary, and it is to be understood, that while I have described and illustrated the preferred embodiment of the invention, I reserve the right to make all changes properly falling within the spirit and scope of the appended claims.

I claim:

1. A wrench head, a handle having one end oscillatably secured thereto, and means slidable on said handle for preventing oscillation thereof, said wrench head and handle having cooperating hammer and anvil surfaces.

2. A wrench head, a handle having one end oscillatably secured thereto, means for preventing oscillation of the handle in the head, and a slidable sleeve on the handle for operation of said means.

3. A wrench head having a socket, an oscillatory handle having a head for bearing contact with said socket, means to retain the handle within said socket, and manually operable means for insertion between one side of the handle and one wall of the socket to prevent oscillation of the handle.

4. In a wrench, a wrench head having a socket formed with a curved bottom, a handle formed with an enlarged head in bearing contact with the curved bottom of said socket, and a securing slip carried by said wrench handle and in contact with the enlarged head of the handle to retain the handle in operative relation to the wrench head.

In testimony whereof I affix my signature.
CHARLES W. LYNCH.
